UNITED STATES PATENT OFFICE.

GEORGE S. SEARLE, OF ROCHESTER, NEW YORK.

STREET SIGN.

Application filed July 15, 1927. Serial No. 205,942.

The present invention relates to street indicating signs and has for an object to provide an improved device of this class which embodies comparatively few parts of simple 5 construction, capable of being manufactured at a relatively low cost and which can be conveniently and quickly applied to lamp posts or other forms of supports by persons of ordinary skill, thus making it unnecessary 10 to employ skilled mechanics for assembling and placing the signs in service.

A further object of the invention is to provide an improved street or highway sign in combination with a lamp or sign post constructed in a manner to receive and cooperate 15 with the post to hold the sign in position without the use of expensive attaching means and in such relationship to the lamp as to afford a high degree of illumination.

20 To these and other ends the invention resides in certain improvements and combinations of parts, all as will be hereinafter more fully described, the novel features being pointed out in the claims at the end of the 25 specification.

In the drawings:

Figure 1 is a view in elevation embodying one form of the invention;

Figure 2 is a fragmentary sectional elevation taken on line 2^a—2^a of Figure 1;

Figure 3 is a top plan view of the sign showing the manner of applying it to the lamp post, the lamp supporting arms being broken away above the sign;

Figure 4 is a transverse section taken on line 4^a—4^a of Figure 2;

Figure 5 is a plan view of the sign holding bracket detached from the post;

Figure 6 is a plan view of the retaining or 40 locking member for the name plate; and

Figure 7 is a section taken on line 7^a—7^a of Figure 1.

Similar reference numerals throughout the several views indicate the same parts.

45 Referring to the drawings, 10 represents a lamp post having a cap or extension 11 thereon provided with opposite projecting portions preferably extended upwardly to form curved arms 12 which extend inwardly 50 at their upper ends to support an annular ring or band 13 into which projects and to which is suitably secured the upper end of a bell-shaped reflector 14 preferably made of porcelain or like material. The reflector is 55 made hollow and provided with a lamp

socket into which is screwed a lamp 16. The wires or circuit connections, not shown, which lead to the lamp socket are preferably carried upwardly through the lamp post and through the hollow arms 12 into the annular member 13 and downwardly to the socket which is suitably secured within the reflector. The base portion 11 of the lamp support is tapered at two sides as indicated at 17 in Figure 2. The lower ends of the arms 12 are 60 preferably cast integral with said tapered portion and are provided with annular enlargements or abutments 18 adjacent the base portion for a purpose which will appear hereinafter.

70 The name plate is indicated at 19 and its supporting bracket at 20. The plate is preferably constructed of relatively thin metal although it may be formed of any other suitable material and, if preferred, may be enameled to prevent rusting. The plate and bracket are preferably made in separate parts to avoid having to enamel the entire sign as well as to permit the name plates to be applied and removed from time to time without removal of the brackets. The bracket is provided with an angularly disposed plate portion 21 which projects upwardly between the abutments 18 at an angle inclined to the axis of the post and is provided at its ends 75 with securing portions 22 which extend on the opposite side of the axis of the post from that on which the body portion of the bracket is disposed and which are adapted to interlock with the arms 12. The securing portions 80 are provided with curved or inclined edge portions 23 which extend behind and engage the abutments 18 at a suitable point thereon whereby to support the bracket in the position indicated in Figure 2 upon one of the 85 inclined faces 17 of the post. Means is provided for cooperation with the name plate to both secure it upon the bracket and to hold the latter in proper position upon the post. This means comprises the clamping plate or 90 member 24 which is preferably constructed similar to the plate 21 of the bracket, having the corresponding securing portions as indicated at 25 and the curved or inclined edges 95 26 which preferably are designed to engage 100 the arms or abutments 18 thereon, the same as the inclined edge portions 23. The plate 24 is also provided with a lip 27 adapted to overlie and engage the upper edge of the name plate as shown in Figures 1 and 2. 110

The bottom edge of the bracket is provided with suitable supporting means for the name plate which is preferably in the form of an upturned lip or edge portion 28. The retaining plate 24 may be secured upon the bracket in any suitable manner either integrally as shown in Figure 7 or as shown attached in Figure 2 by one or more bolts 29 extending through holes 30 and 31 in the plates 21 and 24, respectively. The position of the name plate upon the bracket before tightening up on the bolt 29 is substantially as indicated in Figure 7. In this position, the upper edge of the plate engages the rounded edges of the abutments 18, or what may be termed the under surfaces thereof, so that in effect the abutments form inclined shoulders overlying and engaging the upper edge of the plate to prevent displacement of the latter in an upward direction. By tightening the bolt 29 to pull the clamping plate inwardly to the position shown in Figure 2, that portion of the name plate between the abutments will be deflected inwardly against the resistance of the bottom of the bracket as well as against the resistance of the abutments and the tendency will be to wedge the plate under the rounded or tapered portions of the abutments whereby they will firmly hold it in engagement with the lamp post or the lamp support thereon. The forcing of the name plate inwardly and downwardly as described above also tends to clamp or firmly urge the bracket downwardly upon the inclined portion 17 of the post. Thus the parts are rigidly held in position through engagement of the ends 22 or 25 of the bracket with the abutments at one side of the post and the upper edge of the name plate with said abutments at the opposite side of the post. The name plates may easily be removed by slightly unscrewing the bolt 29 to release the clamping action of the plate, thus permitting insertion and removal of the plates from time to time without removing the bracket or any part thereof. The clamping plate 24 is preferably made separate from the plate 21 but if desired may be integral therewith and bent over and down about the point 31 as indicated in Figure 7.

Where it is found desirable, additional means for securing the bracket upon the post may be provided in any suitable form, such for example, as a band 32 extending partially around the extension 11 of the post and having its ends connected with the bracket in any preferred manner. In the present instance, the ends of the band are extended through lugs 33 on the bracket and bent over as indicated at 34 in Figure 4. The lugs are preferably integral with the bracket, being formed by striking portions of the metal outwardly to occupy substantially right angle positions at the rear side of the bracket.

It will be seen, therefore, that applicant has

provided a lamp post having oppositely extending arms with a lamp support at the upper extremities thereof and with a street sign below the lamp secured upon the arms in a novel manner. It will be understood that the arms at the points where the name plate and bracket engage the same may be enlarged as shown or reduced if preferred so long as suitable abutments are provided for preventing displacement of the parts upon the post. It will be further understood that only one of the arms need be extended to the lamp support 13 and that the other may be terminated at the abutment 18 if it is desired to support the lamp by means of a single arm.

I claim as my invention:

1. In a street indicating sign, a post having oppositely disposed projecting portions, a bracket at one side of the post having portions engaging said projecting portions on the other side of the post, a name plate disposed upon the bracket and having its upper edge engaging the projecting portions on the side on which the bracket is disposed and means on the bracket engaging the upper edge of the name plate between the projecting portions of the post and serving to clamp said upper edge upon said projecting portions.

2. In a street indicating sign, a post having oppositely disposed projecting portions, a bracket at one side of the post having portions engaging said projecting portions on the other side of the post, a name plate having one edge resting upon the bracket and its opposite edge upon the projecting portions on the side on which the bracket is disposed, a member on the bracket engaging the last mentioned edge of the name plate and means serving to clamp said member upon the name plate whereby to clamp the latter upon the post.

3. In a street indicating sign, a post having oppositely disposed projecting portions, a bracket at one side of the post having portions engaging said projecting portions on the other side of the post, a name plate carried by the bracket and having its upper edge engaging the projecting portions on the side on which the bracket is disposed and means for clamping the name plate upon said projecting portions of the post.

4. In a street indicating sign, a post having oppositely disposed projecting portions, a bracket at one side of the post having an angularly disposed plate portion extending between said projecting portions and into interlocking engagement with the same, a name plate carried by the bracket the upper edge of which is disposed in engagement with said projecting portions and means upon the bracket between said projecting portions for clamping the name plate thereon.

5. In a street indicating sign, a post having oppositely disposed projecting portions, a bracket at one side of the post having an an-

- gularly disposed plate portion extending between said projecting portions and into interlocking engagement with the same, a name plate upon the bracket, a member carried by 5 said angularly disposed plate portion in engagement with the upper edge of the name plate and means for clamping said member upon the name plate whereby to bind the upper edge thereof upon the said projecting portions.
6. In a street indicating sign, a post having spaced shoulders thereon, a bracket at one side of the post having end portions extending into engagement with the shoulders 10 on the opposite side of the post, a name plate on the bracket having its upper edge engaging the shoulders at points opposite said end portions and means on the bracket for urging the upper edge of the name plate beneath said shoulders.
7. In a street indicating sign, a post having spaced abutments thereon, a bracket at one side of the post having an angularly disposed portion projecting between said abutments, a name plate carried by the bracket and having its upper edge in engagement with the abutments and a clamping member extending between and engaging the abutments on the opposite side from the name 25 plate and serving to clamp the latter upon the bracket.
8. In combination, a lamp post provided with oppositely disposed arms having a lamp supported thereon, a bracket at one side of the post having portions engaging the arms at the opposite side thereof, a name plate carried by the bracket in engagement with the arms on the side on which the bracket is disposed and means on the bracket for 30 clamping the name plate in engagement with said arms.
9. In combination, a lamp post provided with a lamp and having oppositely disposed abutments beneath the lamp and a bracket 45 at one side of the post extending between the abutments and arranged to support a name plate, said bracket having a plate portion,
- the ends of which engage the abutments on the side of the post opposite that on which the bracket is disposed whereby the bracket 50 is held upon the post.
10. In combination, a lamp post provided with a lamp and having oppositely disposed abutments beneath the lamp and a bracket at one side of the post extending between the 55 abutments and arranged to support a name plate and having at the opposite side of the post end portions adapted to engage the abutments to support the bracket upon the post.
11. In combination, a lamp post provided with a lamp and having oppositely disposed abutments beneath the lamp, a bracket at one side of the post extending between the abutments and arranged to support a name 60 plate and having at the opposite side of the post end portions adapted to engage the abutments to support the bracket upon the post and means for securing the bracket upon the post.
12. In combination, a lamp post provided 65 with a lamp and having oppositely disposed abutments beneath the same, a bracket adapted for supporting a name plate, said bracket being located at one side of the post and having an angularly disposed portion extending 70 between said abutments and a retaining plate for the bracket connected with said angularly disposed portion and having end portions engaging the abutments on the side of the post opposite that on which the bracket is 75 disposed whereby to form a support for the bracket.
13. In combination, a lamp post provided with a lamp and having oppositely disposed abutments beneath the lamp, a bracket at 80 one side of the post extending between the abutments and having portions at the opposite side thereof engaging the abutments to support the bracket upon the post, upper and lower guides carried by the bracket and a 85 name plate inserted upon the bracket between said guides.

GEORGE S. SEARLE.
